UNITED STATES PATENT OFFICE.

WILLIAM H. REESE, OF MILWAUKEE, WISCONSIN.

DESIGN FOR A COLOR-EXHIBITING STAND.

No. 37,598.

Specification for Design.

Patented Oct. 24, 1905.

Application filed April 4, 1905. Serial No. 253,893. Term of patent 3½ years.

To all whom it may concern:

Be it known that I, WILLIAM H. REESE, a citizen of the United States, and a resident of Milwaukee, in the county of Milwaukee and State of Wisconsin, have invented a new, original, and ornamental Design for a Color-Exhibiting Stand, reference being had to the accompanying drawing, in which the figure is a perspective view of the color-exhibiting stand, showing the design.

I claim—
The ornamental design for a color-exhibiting stand as shown.

WILLIAM H. REESE.
